UNITED STATES PATENT OFFICE

JOHN J. GAULT, OF CHICAGO, ILLINOIS, ASSIGNOR TO W. J. NEWMAN COMPANY, OF CHICAGO, ILLINOIS

WELL DRILLING APPARATUS

Application filed October 9, 1929. Serial No. 398,371.

This invention relates to apparatus for drilling any kinds of wells but is particularly intended for use in drilling large wells for foundations, such wells being as from eight to twelve feet in diameter. Such wells 5 may be of any depth but are frequently dug to a depth of one hundred feet or more. On account of the varying materials, encountered in digging such wells, it has been found impractical to use cutting heads of the plow 10 type or those having excavating teeth as the torsion on the driving shaft becomes too great. Furthermore when boulders or rocks 15 are encountered with such plow or scraper types of cutting heads, it is usually necessary to stop the drilling and remove such boulders by other means. The present invention provides a force driven cutting head 20 having rotatable cutting devices which are also free to revolve about the driving shaft whereby objectionable features of the cutter heads heretofore proposed are overcome.

The objects of this invention are; to provide an improved cutting head for drilling wells or the like; to provide an improved well drilling apparatus having a vertical power shaft and a horizontally arranged cutter shaft driven by the power shaft; to provide improved cutters for well drilling; to 25 provide an improved method of drilling wells particularly of large diameter; and to provide such other improvements in construction as will appear hereinafter.

In the accompanying drawings illustrating one form of this invention:

Figure 1 is a vertical sectional view showing the cutter head and driving pipe or shaft; Figure 2 is a sectional view taken on the line 2-2 of Figure 1; and Figure 3 is a 40 detail showing a rock pounding or pulverizing tool.

The hollow shaft or driving pipe 5 is driven by any suitable means and is secured to the bottom section 6 by flanges 7 and 8 and bolts 9. For construction reasons, the flange 8 is

preferably welded to the section 6 after the cutter head has been mounted thereon. The section 6 has a gear 10 at the lower end and is provided with a shoulder 11 forming a support for the bearing 12 of the cutter head 13 which bearing fits over the pipe 6. The cutter head is further held in position by a collar 14 which is secured to the pipe 6 in any suitable manner.

The cutter head 13 has a central rectangular frame or bracket 15 with bearings 16 and 17 in either side thereof. It also has arms 18 and 19 which project outwardly from the upper end of the bearing 12 and which are in turn provided at their outer ends with bearings 20 and 21. A lateral or horizontal shaft 22 is mounted in the bearings 17 and 21. The shafts 22 and 23 are driven from the gear 10 by gears 24 and 25 respectively.

While I have shown only two shafts for the excavating devices any suitable number of shafts may be provided and various forms of cutting, scraping, pounding, drilling or grinding devices may be mounted on these shafts. In the present instance, the shafts are provided with discs 26 having sharpened peripheries and with cutting lugs or curved blades 27 on the sides thereof, as shown particularly in Figure 2. As the shafts 22 and 23 revolve in opposite directions, the cutting lugs on the discs of the respective shafts are accordingly faced in opposite directions as seen from the end of one of said shafts. These discs also preferably increase in diameter from the center of the head outwardly so that when the cutter head rotates on the shaft 6, the rate of travel of the discs on the bottom of the well will be relatively the same. The outer ends of the shafts 22 and 23 are 85 provided with detachable drills or cutters 28 which make the finishing cut to give the well the desired diameter and by substituting longer or shorter cutters, the diameter may be varied within reasonable limits.

The tubular section 6 has spiders or supports 29 which carry a shaft 30 rigidly secured therein and which extends downwardly through a bearing 31 in the frame 15. A 5 fish-tail cutter or drill blade 32 is mounted on the lower end of this shaft and turned thereby.

When a well is to be dug, the pipe 5 is supported and driven by the drilling machine 10 and the water is pumped down there through and out at the bottom of the lower section being discharged between the gears 24 and 25 as indicated by the arrows. When a large pipe is used approximately one thousand gallons of water per minute can be discharged there through which tends to keep the gears free of mud or obstructions. In drilling wells in accordance with my improved method the hole is kept full of water which preferably flows into a sump adjacent to the top of the well and the water pumped therefrom back down through the pipe. I have discovered that in a method of the kind, the effective earth displacement is due largely to the 25 thorough mixing or stirring of the material with the water so that the material will be held in solution or suspension in the water. Having this in mind the excavating devices are designed to cut or loosen relatively small 30 portions or quantities of the earth or clay and thoroughly mix them with the water. As the pipe 5 is rotated, the drill blade 32 will center the drilling head and cut an opening for the gears and center part of the head. 35 As the shaft 5 is turned in a clockwise direction, the friction of the bearing 12 will tend to rotate the drill head in a clockwise direction and the revolving of the cutters on the shaft 23 also tends to rotate the head in a 40 clockwise manner. This rotation is however resisted by the action of the cutters on the material encountered. As a consequence both sets of cutters will tend to cut into the surface as they rotate on their axes and there 45 will be a rolling and churning action as these cutters revolve about the vertical axes of the cutter head. This will tend to thoroughly pulverize and loosen the surface of the material in the bottom which will be mixed with 50 the water and carried upward to be discharged at the top of the well. The cutting may be increased by adding weights to the cutter head or to the driving pipe and such weight is gradually increased as the well 55 becomes deeper due to the heavy pipe used for driving.

If stones or boulders are encountered, the rotation of the cutter head may be stopped but the cutting discs will continue to revolve 60 on their axes and will work against such stones or boulders and will tend to loosen them or else break them up or grind them away. During this operation, the head may be slightly raised, or merely supported on 65 the surface so that the cutters will be free to

act against the stone or boulder. If desired breakers or beaters 33, such as shown in Figure 3, may be substituted for the discs. These heavy pounding or breaking devices will further tend to rapidly pound away or break up any rocks or boulders encountered in the drilling.

From this description, it will be seen that with suitable discs or wheels running around on the bottom of the well, each disc will tend to make a circular track and the various discs may be placed in staggered relation so that each disc will make its own track around the bottom of the well. The cutting blades on the sides of the discs shown will also tend to loosen and raise the material which will be washed off by the water and rapidly put in condition so that it will be dissolved or suspended in the water. While the main cutting proceeds on the bottom of the well, the bits or scrappers 28 will act on the sides of the well to trim the same and keep it of uniform diameter.

My improved cutter head may be varied in the details of construction in order to 90 adapt the same for cutting different materials or for different sized wells and other changes may be made within the scope of this invention as set forth in the following claims in which I claim:

1. In a well drilling apparatus, the combination of a vertical rotating driving shaft, a cutter head revolvably mounted on said shaft, laterally arranged shafts mounted in the cutter head, means for rotating the lateral shafts by the first named shaft and cutting devices secured to said lateral shafts.

2. In a drilling apparatus, the combination of a vertically arranged driving pipe, a frame rotatably mounted at the lower end of said pipe, horizontally arranged shafts mounted in said frame, gears for driving said shafts from the pipe and cutting devices mounted on said shafts, the arrangement being such that water may be forced through 100 the pipe and past the gears for keeping the gears clean and to assist in the drilling operation.

3. In a drilling apparatus, the combination of a vertically arranged rotatable pipe 115 having a gear at the lower end thereof, a frame rotatably mounted on the pipe above said gear, horizontal shafts mounted in said frame, gears on said shafts meshing with the gear on the pipe, a plurality of disk-like cutters mounted on said shafts, a shaft secured in the pipe and projecting downwardly through the frame and a drill secured to the lower end of the last named shaft.

4. A drilling apparatus of the character 125 set forth, comprising a sectional driving pipe through which water may be pumped, a beveled gear at the lower end of said pipe, a frame rotatably mounted on said pipe at the lower end thereof and having outwardly pro- 130

jecting arms, horizontal shafts mounted in said frame and having bearings in said arms, beveled gears on said shafts which engage with the first named gear, a plurality of circular excavating devices mounted on said shafts, cutting bits secured to the ends of said shafts, a shaft secured in the lower end of the pipe and extending downwardly through a bearing in the frame and a drilling point mounted on the end of the last named shaft.
